CLAIM

The ornamental design for a twisted cane, as shown and described.

DESCRIPTION

FIG. 1 is a top plan view of a horizontal handle twisted cane showing my new design;

FIG. 2 is a bottom plan view thereof;

FIG. 3 is a front view thereof;

FIG. 4 is a rear view thereof;

FIG. 5 is a right side view thereof;

FIG. 6 is a left side view thereof;

FIG. 7 is a perspective view thereof; and,

FIG. 8 is a partial side view illustrating a hook handle twisted cane.

The surface(s) or portion(s) of the article not shown in the drawing or described in the specification form(s) no part of the claimed invention.
